VACUUM TUBE CONSTRUCTION

Charles J. Kayko, Jackson, Mich., assignor, by
mesne assignments, to The Sparks-Withington
Company, Jackson, Mich., a corporation of
Ohio

Application August 31, 1929. Serial No. 389,820

4 Claims. (Cl. 250—27.5)

My invention relates to vacuum tubes of the type employing uni-potential cathodes provided with cathode heaters energized by alternating current.

5 An object of my invention is to devise an improved vacuum tube structure for supporting the elements of the tube in proper spaced relation.

A further object of my invention is to devise an 10 improved structure of the cathode element with its heating unit to reduce the alternating current hum due to the heater energizing circuit.

My invention is illustrated in the accompanying drawing in which:

15 Figure 1 is a view in elevation, partly in section, showing the tube elements mounted upon the stem;

Figure 2 is a side view of Figure 1;

Figure 3 is a sectional view of Figure 1 taken 20 along the line 3—3;

Figure 4 is an enlarged sectional view of the cathode cylinder with its heater unit;

Figure 5 is a sectional view of Figure 1 taken along the line 5—5.

25 Referring to Figure 1, only the internal structure of the tube is shown; the envelope and its base having been omitted for the purpose of better showing. 1 indicates the stem of the tube which is provided with the usual "pinch" 1a into

30 which is embedded two parallel rods 2 and 3. The upper ends of rods 2 and 3 pass through apertures formed in a strip of mica 4, which serves to maintain the free ends of these rods in proper spaced relation, and also serves as an

35 insulating support for the grid and cathode elements, as will be seen hereinafter. The mica strip is held against longitudinal displacement along the rods by pinches 2a and 3a formed on rods 2 and 3, respectively. A cylindrical plate

40 element 5 is located between rods 2 and 3 and is supported by rod 3. The wire coil 6 forming the grid element is located within plate element 5, and is supported by a rod 7, one end of which extends through an aperture formed in mica

45 strip 4, and the other end being welded to an angle rod 8 embedded in pinch 1a. Each turn of the grid coil is preferably welded to rod 7 at the point of contact.

The uni-potential cathode element is located 50 within the grid coil 6 and comprises a cylinder 9 of nickel or other suitable metal, the upper end of which is spot welded to a metallic rod 9a passing through an aperture in mica strip 4, and being supported from rod 2 by a cross-rod 9b. The

55 upper flattened end of the cathode cylinder 9

serves to prevent downward displacement of the mica strip 4 on rods 2 and 3. The heater element for the cathode comprises a hair-pin filament 10 threaded through two parallel holes formed in a quartz rod 11, the heater unit being 60 inserted within the cathode cylinder 9, and the terminals of the filament being welded to rods 10a and 10b embedded in the pinch of stem 1. There is sufficient frictional resistance between the cathode cylinder 9 and the quartz rod 11 to 65 support the heater unit from the cathode cylinder. The ends of the filament serve to maintain the lower end of the heater and cathode elements in proper position and prevent lateral displacement. Rods 2, 3, 8, 10a and 10b are provided with terminal conductors 2b, 3b, 8a, 10c and 10d, serving as leading-in wires for the cathode, plate, grid and heater elements, respectively. An insulated rod 12 is also embedded in the pinch 70 of the stem and carries at its free end a cup 12a 75 containing flashing material.

In the manufacture of my tube, I prefer to assemble the structure in unit assemblies which in turn are assembled to complete the entire tube structure. The stem assembly is preferably 80 formed by sealing into the pinch of the stem six wires of equal length, corresponding to rods 2, 3, 8, 10a, 10b and 12. These wires are embedded in the pinch in one operation, and are then cut to proper length and formed to the proper shape. 85

The grid assembly is formed by winding the wire coil 6 onto an arbor of particular configuration to give the coil the special shape shown in Figure 3, and each turn of the coil is welded to the support rod 7. The rod 7 may be incorporated in the arbor and the wire 6 wound directly over it. 90

The plate element 5 is formed from a single sheet of metal as indicated in Figure 3, the ends of the sheet forming the element being extended 95 in parallel lips 5a and 5b to embrace rod 3.

The cathode element is formed by rolling a sheet of metal, preferably nickel, into a cylindrical form having a lap seam and an inside diameter large enough to receive quartz rod 11 100 (see Figs. 3 and 4). The rod 9a is then inserted into one end of the cylinder which is then flattened against the rod and welded thereto as by spot welding. The cathode cylinder 9 is next coated with suitable material 20 to increase its 105 electron emission over the portion which lies within the grid element.

The heater unit is formed by cutting to proper length the quartz rod 11 and threading the hair-pin filament 10 through the parallel holes in the 110

rod, leaving sufficient terminal extensions on the filament for welding to the rods 10a and 10b. The heater unit is next inserted into the open end of the cathode cylinder.

5 With the unit assemblies formed as indicated above the assembly of the completed tube structure is as follows: The formed plate element is placed in position upon rod 3, and the lips 5a and 5b are welded together and to the rod 3 by spot welding. The grid assembly is placed in position within plate 5, and the lower end of rod 7 is welded to angle rod 8. The mica strip 4 is placed over the rod 9a on the cathode and heater unit assembly, and this assembly is inserted into the 15 grid coil 6, the rods 2, 3 and 7 being guided into their respective apertures in mica strip 4. The ends of filament 10 are bent at right angles and welded to rods 10a and 10b. The mica strip 4 is pressed against the upper flattened end of cathode cylinder 9, and pinches 2a and 3a are then formed in rods 2 and 3, respectively. With the 20 end of the cathode cylinder 9 held firmly against mica strip 4, the rod 9b is welded to rod 9a and rod 2 to provide mechanical support for the cathode and heater units. It will be seen that mica strip 4 serves to prevent lateral displacement of the upper ends of the cathode and grid elements.

From an inspection of the structure which I have devised, it will be seen that the uni-potential cathode cylinder completely shields the entire electron emitting portions of the heater filament 10 and substantially eliminates any disturbing hum due to alternating current flowing in the 35 heater circuit. The lower ends of the filament which are not covered by the cathode cylinder do not operate at a temperature sufficient to cause substantial electron emission, due to the conduction of heat away from the filament by the rods 40 10a and 10b. Furthermore, the electron emitting area of the cathode cylinder is limited to that area contained within the grid element, and the portions of the cylinder extending beyond the ends of the grid serve simply as shielding 45 elements. By this structure direct electron emission from the heater filament to the plate element is avoided, and the electrostatic influence of the heater circuit upon the electron stream between the cathode and the plate is reduced 50 to a minimum. It will also be seen that I have devised a structure in which the electrical connection to the uni-potential cathode is made at a point symmetrical to the cathode axis and external thereof.

55 What I claim is:

1. In a vacuum tube structure, the combination of a stem having a single pinch, two spaced rods embedded in the pinch, an insulating spacer

60

65

70

75

mounted upon said rods near the free ends, a cathode and a heater therefor positioned between said rods, means including leading-in conductors for said heater for supporting one end of said cathode from said pinch, and means including a metallic conductor passing through an aperture in said insulating spacer for supporting the other end of said cathode from one of said rods, said last mentioned means and rod serving as a leading-in conductor for said cathode.

2. In a vacuum tube structure, an evacuated vessel comprising a press, a plurality of metallic members held in said press, two of said metallic members extending substantially the full length of said vessel and the remainder terminating a short distance from said press, an anode supported by one of said long metallic members, a cylindrical cathode connected axially symmetrically at one end to said other long metallic member, an insulating spacer mounted upon the free ends of said long metallic members, a heating element within said cathode and insulated therefrom, said heating element being connected to and supported by two of said short metallic members, said heating element support providing means for preventing lateral displacement of the free end of said cathode.

3. In a vacuum tube structure, the combination of a stem having a single press, two spaced rods imbedded in said press, a cathode arranged between said rods, an anode surrounding said cathode and supported by one of said rods, an insulating spacer mounted upon said rods near their free ends above said anode and cathode, and means for supporting said cathode from and making electrical connection with the other of said rods, said means passing through an aperture in said spacer whereby said cathode is held against lateral displacement.

4. In a vacuum tube structure, an evacuated vessel comprising a press, a plurality of metallic members held in said press, two of said metallic members extending substantially the full length of said vessel and the remainder terminating a short distance from said press, an insulating spacer mounted upon the free ends of said long metallic members, a cathode, a grid surrounding said cathode supported at one end by one of said short metallic members and at the other end to said insulating spacer, an anode surrounding said grid supported by one of said long metallic members, and means for connecting to and supporting said cathode from the other long metallic member, said means passing through an aperture in said spacer whereby said cathode is held against lateral displacement.
